The ornamental design of a bell tower shelter, as shown and described.

DESCRIPTION

FIG. 1 is a perspective view of a bell tower shelter, showing my new design;

FIG. 2 is a top plan view, the bottom being plain and unadorned;

FIG. 3 is a front elevational view, the rear being a mirror image thereof; and,

FIG. 4 is a side elevational view, the opposite side being a mirror image thereof.
